UNITED STATES PATENT OFFICE.

RICHARD M. VAN VALKENBURGH, OF KANSAS CITY, MISSOURI, ASSIGNOR TO IRVING-PITT MANUFACTURING COMPANY, OF KANSAS CITY, MISSOURI, A CORPORATION OF MISSOURI.

BINDER.

Application filed October 12, 1925. Serial No. 61,976.

This invention relates to loose leaf binders of the type generally known and designated as the "county record book" but may be applied as a novel feature to any loose leaf book of the general character illustrated.

The primary object of the present invention is the provision of effective means for quickly and securely engaging the posts of the binder without encountering the trouble usually incident to this work when the ordinary type of binder post and locking means is used.

The usual method of locking the hingedly mounted binder top to the several posts consists of aligning each of the posts so that the respective post engaging pin may enter a transverse hole formed in each. The faults and short comings of the binder now in use need not further be mentioned.

It is an object of this invention to provide novel post engaging means which includes means for retaining each of the posts in the proper lock member engaging position.

A still further object of this invention is the provision of a post engaging means which is hingedly carried by a support plate attached to the binder cover and which carries the post locking member.

An even further object of this invention is the provision of a binder post having oppositely disposed notches in each of its ends whereby the locking member may engage the same after all the posts have been engaged by a guide member which supports the post locking means. Other objects pertaining to the compactness of structure, neatness and simplicity of design and the lack of a large number of complicated parts, will be set forth in the following specification referring to the accompanying drawings in which;

Figure 1 is a perspective view of a loose leaf binder constructed in accordance with the present invention.

Fig. 2 is an enlarged vertical section of the binder taken on line II-II of Fig. 1.

Fig. 3 is an enlarged fragmentary detailed cross section of the binder taken on line III-III of Fig. 2 and showing the same with the top or one of the covers thrown back to the open position.

Fig. 4 is a view similar to Fig. 3 with the book in the closed position.

Fig. 5 is a perspective view of the post

engaging member showing the slidably mounted post lock mounted thereon.

Fig. 6 is an enlarged broken plan view of one end of the post engaging and locking means showing one method of permanently locking the post locking means in the closed position.

Fig. 7 is a plan view of the open binder showing another way of hingedly mounting the post engaging member to the support plate.

Fig. 8 is an end view of the binder shown in Fig. 7, and

Fig. 9 is an enlarged perspective view of one of the binder posts entirely removed from the remaining structure.

Like reference characters refer to similar parts throughout the several views, and the number 10 designates the covers of a loose leaf binder which may be bound together by a back 12 and which contains the ordinary loose leaf sheet 13.

In describing the post engaging member and locking means, together with the several minor parts, it should be borne in mind that there is a similar structure supported or carried at the top and bottom of the sheets 13 by each of covers 10. A support plate 14 is rigidly attached to each cover 10 by rivets or analogous means 15 with a portion thereof extended beyond the hinged edge 80 of cover 10 to form a hinge eye 16 at each of its ends. A hinge pin 17 is carried by each hinge eye 16 and, in the instance shown rigidly engages a post engaging member 18 whereby the same is hingedly supported to support plate 14 and thence to cover 10. For the purpose of illustration, three sheet carrying posts 19 have been shown, but it is understood that the invention may be used in connection with any number of posts 95 which may be required to effectively hold sheets 13 in place. As is shown in Fig. 9 each of posts 19 is provided with a notch 20 adjacent each end thereof, said notches facing or opening out on opposite sides or edges of the post.

Each post engaging member 18 has an opening 21 adapted to register with each post 19 when post engaging member 18 has been pressed against the stack of sheets 13 to be bound in the book. To facilitate the action of passing post 19 through opening 21 of post engaging member 18, a guide means in the form of a wall 22 may be

formed integrally with member 18. This wall 22 engages the bound edges of the sheets 13 and tends to prevent their curling or ruffling in the binder, and when wall 22 has 5 engaged the edges of sheets 13, it will be seen that opening 21 will be in a position to allow the passage of posts 19 there-through. This wall 22 may be of any width up to and including half the distance between the stack 10 of sheets 13, but it is preferred to construct it substantially as shown in the drawing.

After post 19 has been engaged by post 25 engaging member 18 by passing through openings 21, the locking mechanism is 15 brought into play to rigidly hold the posts and all the related binder parts in the bound position. Each end of post 19 has passed far enough through post engaging member 18 to allow the notch 20 to be entered by a locking bar 23 slidably mounted through the means of a well known slot and pin construction 24 to the sheet engaging member 18. This locking bar 23 is also provided with openings 25 which register with openings 21 with the post engaging member 18 when the bar is in the unlocked position. This permits the passage of post 19 there-through, yet allows bar 23 to be moved so that a portion thereof adjacent each opening 25 will enter notch 20 to grip the post and keep the same from being moved in any direction. The notches 20 of each post 19 are provided with inclines which continue from the sides nearest the end of the post 30 as shown in Fig. 9, and which act as guides or guide faces for bar 23. This facilitates the entry of bar 23 and does not require that the bar and notches be in close alinement before the locking movement is imparted. 35 A finger engaging member 26 may be provided on member 23, and a transverse crimp 27 formed in post engaging member 18 to act as a positive positioner and to more or less retain member 23 in the post locking 40 position.

It will be seen that through the use of the post engaging member 18 and the openings 21 formed therein, that no time is lost in positioning all of the posts of the binder in place to immediately receive the locking bar 23. It is preferred to have the upper and lower locking bar of each binder move in opposite directions to engage the oppositely facing notches 20 of post 19 as shown 45 in Figs. 2 and 9. Support plate 14 should also be notched to avoid striking the tops of posts 19 and to permit the binder to be closed to take up the least amount of room as shown in Fig. 4. It is not particular at what point on post engaging member 18 the hinge pin 17 is attached. It may, if desired, be attached to wall 22 of this member, or if desired the well known piano hinge construction may be used between post 50 engaging member 18 and support plate 14.

As a means for permanently locking the binder after the desired entries have been made on all the sheets contained therein, any well known means may be used to prevent the further manipulation of locking bar 70 23, but it is preferred to use a depressible lug and notch construction as shown in Fig. 6. The lug 29 which is formed between two slits cut in the head of the pin of the slot and pin construction 24 is punched down 75 into notch 30 formed in the slot through the use of some sharp instrument. Fig. 6 shows the locking bar 23 in the open or unlocked position with the notch 30 clearly shown. When the bar is in the locked or closed position, notch 30 falls directly beneath the cut-out lug 29 and will easily and effectively receive the same whenever it is desired to permanently lock the binder in such a way that the removal of sheets without mutilating the same is prevented.

The operation of this novelly constructed binder has been made clear through the specification and to one familiar in the art, it 90 will be unnecessary to follow out step by step the manner of removing and inserting a sheet.

Having thus fully described the invention, to the specific details of which it is desired not to be limited, what is claimed and desired to be secured by Letters Patent is;

1. A loose leaf binder comprising a pair of covers hingedly connected by an arcuate back, a support plate rigidly attached to each of said covers, separable sheet receiving posts, a pair of post engaging angle bars, means permanently carried by each post engaging angle bar for locking the same to said posts and means for hingedly mounting each of said post engaging angle bars to a support plate.

2. A loose leaf binder comprising a pair of covers hingedly connected by an arcuate back, a support plate rigidly attached to each of said covers, sheet receiving posts and a post engaging member hingedly carried by each support plate respectively, said members each having guide means adapted to abut the bound edges of a predetermined number of the sheets in said binder.

3. A loose leaf binder comprising a pair of covers hingedly connected by a back member, a support plate rigidly attached to each of said covers, a post engaging member hingedly carried by said support plate, sheet receiving posts and a guide member abutting the bound edges of a predetermined number of the sheets integral with each post engaging member movable therewith and independently of the other of said guide members whereby the same is directed to engagement with said posts as its associated cover is turned about the cover interconnecting back member.

4. In a loose leaf binder, a pair of covers,

a plate rigidly secured to each cover respectively and a post engaging angle bar hingedly carried by each plate respectively, one wall of said angle bar having means for releasably engaging said posts as the other wall thereof extends therefrom to abut a predetermined number of the binder sheets held by said posts.

5. In a loose leaf binder, sheet receiving 10 posts each having notches adjacent each end thereof, post engaging members having a locking member in juxtaposition thereto, openings formed by said post engaging members and the respective locking member 15 through which said posts are adapted to pass to be locked in place by the sliding of said locking member into engagement with said notches, means for maintaining said locking member in slidable engagement with the face 20 of said post engaging member and a locking lug carried by said maintaining means adapted to register with a notch in the post engaging member and to be forced thereinto to permanently lock said locking member 25 against further movement when in its post-locking position.

6. In a loose leaf binder having a pair of covers hingedly connected by an arcuate back, sheet receiving posts, a pair of post 30 engaging members, means for hinging each post engaging member to the adjacent cover and means including a projecting wall integral with each post engaging member adapted to guide its supporting cover to the 35 proper closed position by abutting the bound edge of a predetermined number of the binder sheets whereby, when said guide means is in the sheet abutting position the binder parts may be moved to secure the 40 same against displacement.

7. In a loose leaf binder, sheet receiving posts, a post and sheet engaging member, a post locking means slidably mounted on said engaging member and means for permanently locking said post locking means in the locked position comprising a headed pin supported by said post engaging means having a portion of its head set off by parallel slits said set off portion adapted to be forced 50 into an opening in said post locking means when said means is in the locked position and said opening under-lies said set-off portion.

8. In a loose leaf binder having a pair of 55 covers hingedly connected by an arcuate back, sheet receiving posts, a plate rigidly secured to each of said covers, a pair of post engaging members each having locking means for immovably securing the same to 60 said posts and against the sheets in said binder, said post engaging members being hinged adjacent the rearmost edge of the plates respectively and each having an inwardly extending guide wall abutting a predetermined number of the binder sheets at 65

their bound edge whereby the said post engaging member is held immovable as the respective cover is hinged to the closed position.

9. In a loose leaf binder of the character 70 described having sheet supporting posts, a pair of hingedly mounted post engaging members comprising members each having sides disposed at right angles to each other, one of said sides adapted to engage said 75 binder posts and the face of the sheets as the other of said sides engages the bound edges of a predetermined number of said sheets, said edge abutting sides projecting toward each other and terminating in spaced relation.

10. In a loose leaf binder, a support plate 80 rigidly attached to each binder cover and a post and sheet engaging means hingedly carried by each support, each support plate 85 engaging its respective post and sheet engaging means at its rearwardly extending edge and formed to lie edge to edge and in the same plane with said post and sheet engaging means when said covers are closed. 90

11. In a loose leaf binder of the character described, a pair of covers hingedly connected by an arcuate back, a support plate 95 rigidly carried by each cover and a sheet engaging angle bar hingedly connected to said support plate adjacent the meeting edge of the two sides of said angle bar.

12. In a loose leaf binder of the character described, a pair of covers hingedly connected by an arcuate back, each of said covers 100 having an angle bar hingedly secured thereto, said angle bar having post engaging and locking means carried by one of the sides thereof, the other side adapted to engage the bound edges of the binder leaves when in the 105 post engaging position.

13. In a loose leaf binder of the class described, a pair of covers, a plurality of sheet 110 engaging posts, an arcuate back joining said covers and an angle bar hingedly supported by each of said covers, one of the sides of each bar extending toward the corresponding side of the other when the binder is in the closed position, said inwardly directed sides abutting the bound edges of said binder 115 sheets.

14. In a loose leaf binder of the character described a pair of covers hingedly connected by a flexible back, a support plate 120 carried by each cover, an angle bar hingedly connected to each support plate and a plurality of sheet carrying posts carried by said angle bars, the body of each support plate adapted to lie in the same plane with one wall of its supported angle bar when its 125 carrying cover is closed.

15. In a loose leaf binder of the character described, a pair of covers hingedly connected by a flexible back, a support plate 130 carried by each cover and projecting beyond

the edge thereof, joined by said back, an angle bar hingedly connected to each support plate and a plurality of sheet carrying posts carried by said angle bars, the axis of the hinge being above one wall of said angle bar and intermediate the two edges thereof.

16. In a loose leaf binder of the character described, a pair of covers hingedly connected by a flexible back, a support plate carried by each cover and projecting beyond the edge thereof, joined by said back, an angle bar hingedly mounted to each support plate and a plurality of sheet carrying posts carried by said angle bars, one wall of each

angle bar abutting a predetermined number of the binder sheets, the other wall thereof having a releasable post lock, slidably mounted thereon, the axis of the respective hinges being above said rock supporting wall and intermediate the two edges thereof, each of said support plates being formed to permit its body portion to lie in the same plane with the lock supporting wall of its supported angle bar when its carrying cover is closed.

25 In testimony whereof I hereunto affix my signature this 9th day of October, 1925.

RICHARD M. VAN VALKENBURGH.
